METHOD OF AND MEANS FOR REGISTERING
IMPRESSIONS IN MULTIUNIT SHEET
PRINTING MACHINES

Alexander J. Albrecht, West New York, N. J., assignor to R. Hoe & Co., Inc., New York, N. Y., a corporation of New York

Application June 14, 1946, Serial No. 676,733

29 Claims. (Cl. 101—183)

1

The present invention relates to sheet fed multiple unit rotary printing machines and more particularly to the gripping mechanism for the sheets being fed through the press and to methods of correcting registry.

In printing machines of this type the sheets are fed from one unit of the press to the succeeding unit, an impression being made thereon by each unit. All these impressions must be in register. Gripping devices, usually mounted upon a gripper bar mechanism, are employed for holding the sheets against the successive cylinders of the press and are so constructed and arranged as to provide for proper axial and peripheral alignment of the sheet with the cylinders for insuring register. Several forms of this arrangement are in use, and two of these are fully described and illustrated in Patents Nos. 2,138,405 and 2,100,852 which describe a conveyor type press and a transfer cylinder type press, respectively.

It has been found that the sheets, while going through the various units of the press, will frequently warp or distort, especially at the trailing end, due to the effect of atmospheric and press conditions, together with the mangling action of the cylinders between which the sheet passes. Such effects are most noticeable in offset presses, in which the water used has a tendency to humidify the sheets and expand their trailing edges. The leading or forward end of the sheet, where it is clutched by the gripping fingers, is usually not materially affected but the trailing end will spread laterally or perhaps shrink, due to moisture and other conditions. In presses where heating, air drying and the like devices are utilized between units, further distortion effects may occur. As a result, although the later impressions will be in register at the leading or forward end of the sheet, as well as down the center of the sheet, those at the rearward or trailing end of the sheet, especially toward the margins thereof, will be out of register. The amount of such distortion is small but in such work it is necessary that it be corrected.

It has also been found that under certain conditions, piled sheets will sometimes absorb moisture which expands one or more of the edges of each sheet, causing a fullness or slight ruffling at the edge, and when such sheets pass between the cylinders of the printing machine, there is a considerable tendency for this fullness to become localized and produce one or more wrinkles in the sheet. This condition can be overcome by the means herein disclosed.

A purpose of the present invention is to provide a method of warping a sheet in such a way

2

as to distort the trailing edge thereof for correcting registry of the impressions thereon without substantially affecting registry of the impressions on the leading edge of the sheet.

5 A further purpose of this invention is to provide means for bowing or bending the gripper bar mechanism by which the sheet is held in such a way as to warp the sheet and bring its trailing edge back into registry without affecting the leading edge of the sheet.

15 Another object of the invention is the provision of means for controlling the degree of bowing of the gripper bars at the individual cylinders of the press, since it has been found that correction is most necessary at the third and any following units, the paper having been warped out of shape during its passage through the earlier units.

20 Another object is the provision of simple, inexpensive and easily installed mechanism for achieving the above purposes, which may be simply and quickly adjusted by the operator when desirable, and which will also provide means for preventing sheets that have been expanded along one edge from wrinkling as they pass through the machine.

25 With these and other objects in view, as may appear from the accompanying specification, the invention consists in the method of operation, combinations of parts and features of construction which will be first described in connection with the accompanying drawing, showing gripper bar bending mechanisms embodying the invention in two preferred forms, and the method and features forming the invention will then be specifically pointed out in the claims.

30 In the drawings:

Figure 1 is a diagram illustrating the corrective action upon a sheet passing through a press embodying the present invention, which sheet has previously spread at its lower end;

35 Figure 2 is a similar diagram to Figure 1, but in which the sheet has been shrunk at its lower end during its passage through the press;

40 Figure 3 is a diagrammatic view of a chain conveyor type of multiple unit press in which the present invention may be embodied;

45 Figure 4 is a longitudinal section through a cylinder of the press shown in Figure 3, showing the gripper bar mechanism embodying the present invention;

50 Figure 5 is a sectional view on the line 5—5 of Figure 4;

Figure 6 is a sectional view on the line 6—6 of Figure 4;

55 Figure 7 is an end view of the cylinder illustrated in Figure 4;

Figure 8 is a diagrammatic view illustrating the operation of the present invention;

Figure 9 is a diagrammatic view of a transfer cylinder multiple unit press in which the present invention may be embodied;

Figure 10 is a top plan view of an impression cylinder of the type employed in the press illustrated in Figure 9, embodying the present invention;

Figure 11 is an end view of the impression cylinder illustrated in Figure 10, with a portion broken away;

Figure 12 is a sectional view on the line 12-12 of Figure 10;

Figure 13 is a sectional view on the line 13-13 of Figure 11; and

Figures 14 and 15 are, respectively, similar to Figure 7 and a portion of Figure 4 and show a modified form of the invention.

Figures 1 and 2 are diagrams provided to illustrate the method of correcting register embodied in the present invention. As previously stated, a sheet, after passing through one or more units of a multiple unit sheet fed press, is affected by atmospheric conditions and becomes distorted. In some presses, this is due to the excessive moisture inherent in the method of printing used, as in offset presses. The mangling action of the cylinders between which the sheets pass, together with temperature variations, may also cause some distortion of the sheets.

Referring to Figure 1, the sheet A has been previously distorted, its trailing edge having been spread as indicated in solid lines, whereas the leading edge B, which is gripped by the gripping mechanism C of the press, remains unaffected. The usual mechanism provided for gripping the sheet in proper position to ensure registry will control its position sufficiently to keep the printing on the upper or leading end in registry, and the printing through the center of the sheet will also remain in register. However, at the sides of the lower edge of the sheet the registry is affected. The primary impressions, indicated by the broken lines D, will spread as the paper itself stretches. Thus, the impression made by the succeeding unit (say, the third or any later unit of a multiple color press) will be in register at the top of the sheet and through its center, but will be out of register at the sides of the trailing lower end of the sheet. By pulling the center of the sheet forward at its center, as shown by the dotted lines E, the leading edge of the sheet is bent in the tangent plane common to both cylinders at the impression line or point and is warped as it passes through the printing couple, its side edges near the trailing edge being drawn toward the center, and the impression indicated by the line D will be simultaneously drawn toward the center to become parallel to the center line as indicated at F and thus register with the impression made by the succeeding unit.

Figure 2 illustrates the method as applied to a sheet which has shrunk at its lower end, as indicated in solid lines. The impression thereon, indicated by the broken lines D, would be out of register at the sides toward the lower end of the sheet. By pushing the leading edge of the sheet backward at its center or advancing its edges, as at E, the trailing end of the sheet will be caused to spread as it goes through the printing couple, whereupon the printing thereon resumes its correct position parallel to the center line and in register with the succeeding impression, as indicated by the dotted line F.

In both of the figures the dotted outline E represents the sheet after it has been warped back into its original shape. It is to be understood that the degree of distortion is quite small and has been exaggerated for purposes of illustration, but in high grade printing work even a very slight lack of register is undesirable. Only a slight warping of the leading edge of the sheet, as obtained through a slight shifting of the position of the gripping mechanism at the center, is necessary to make the correction.

This method of correcting register where sheets have become distorted during the printing process is applicable to any type of automatic sheet fed multiple unit press. Means for carrying out the method are discussed below with reference to conveyor type presses and transfer cylinder type presses, in both of which the sheets are held by gripping fingers as they are carried through the press and about the impression cylinders.

In Figure 3 is illustrated a multiple color offset type press embodying a chain conveyor 1 for carrying the sheets from the sheet feeding unit 2 and registering unit 2a through the various printing units 3 of the press. Three such printing units are shown, but it will be understood that any desired number may be employed. Attached to the chain conveyor 1 are gripper bar units 4, each of which comprises a telescopic tubular bar 5 to which is affixed a number of grippers 6 (Figures 4, 5 and 6). The construction of the gripper bar and its attached grippers is described in Patents Nos. 2,231,914 and 2,286,032, together with its operation and integration in a printing machine of the type in question.

The ends of the telescopic bar 5 are held in carrying members 10 (see Figure 4) which are attached to the conveyor chain 1. The conveyor chain (as described in the above-mentioned patent) cooperates with sprocket teeth 11 formed on a projection of the end plate of the impression cylinder 12. A roller 15 is also carried by each carrying member 10, and cooperates with a cam or track member 16 attached to the frame of the press and following the contour of the cylinder 12, for pressing the bar 4 downward within a channel 20. The channel 20 is formed in the body of the cylinder 12 for receiving the gripper bar 4 as it is carried by the chain 1 over the cylinder. The roller 15 and cooperating track 16 act to force the carrying member 10 and its associated gripper bar 4 into the channel 20 toward the axis of the cylinder 12, as the chain conveyor 1 travels over the sprocket teeth 11 of the rotating cylinder.

It is to be understood that the structure thus far described is duplicated at either side of the press and at either end of the cylinder 12, although only one end has been illustrated in the drawings.

The gripper bar 4, being of considerable length as compared with its diameter, is supported upon sets of rollers located in the channel 20, to prevent its sagging toward the center of the cylinder. In the present construction, these rollers are carried by rods running longitudinally within the channel 20 and supported by bearing blocks 30, 30' attached to the bottom of the channel 20, as illustrated in Figures 4-6. The rollers 31 are carried by a shaft or rod 32 (left hand side of illustrations). This shaft 32 is held in the bearing blocks 30 and 30' in any suitable manner and may, if desired, terminate in one end of the cylinder 12.

The second set of rollers, 33, are carried by an eccentric rod or crank shaft 34, which is formed

in three sections. The first section is journaled in one end of the cylinder 12, extending therethrough, and extends toward the center of the cylinder to the first bearing block 38, in which it is also journaled. Inwardly of this block 38, the shaft or rod is of a reduced diameter, with its center eccentric to the center or axis of the first portion of the rod. This reduced diameter eccentric portion 34' of the rod 34 extends along the channel to the second bearing block 38', at which point the eccentric ends and the extension of the rod, of lesser diameter than the eccentric portion, has its center in alignment with the center or axis of the first portion, thus forming a crank or eccentric. This third portion of the rod 34 is journaled in the block 38', for rotation therein.

The rollers 33 are mounted for rotation upon the eccentric portion 34' of the rod or shaft 34. Both the rollers 31, mounted upon the shaft or rod 32, and the rollers 33, mounted on the eccentric 34', are held against their adjacent bearing blocks by lock rings or clips 35, to prevent longitudinal movement of the rollers on their supporting shafts. The bearing blocks and their associated pairs of rollers are preferably located approximately one-third of the distance in from the ends of the cylinder 12, for supporting the gripper bar 4.

The rod 34, extending through the end of the cylinder 12, has a sector plate 40 keyed to its outer end for rotary movement therewith. The plate 40 has an arcuate slot 41 formed therein through which a bolt 42 is inserted for threaded insertion into the adjacent end plate of the cylinder 12. By loosening the bolt 42, the plate 40 may be rotated as permitted by the arc of the slot 41, thus rotating the shaft 34 and consequently swinging the eccentric portion thereof on which the rollers 33 are mounted.

Figure 8 shows diagrammatically the effect of adjustment of the plate 40 and rod 34, indicating one extreme of adjustment on solid lines and the opposite extreme on dotted lines, the normal position, not shown, being an intermediate one. When the rod 34 is rotated, the position of that portion of the gripper bar 4 which rests upon the rollers 31 and 33 is altered. Upon rotation of the shaft 34 clockwise, the rollers 34 are moved away from the rollers 31, toward the position shown in solid lines and allowing the bar 4 to move to the right, with the axis of the portions of the bar engaging the roller 33 shifting on an arcuate line about the center of the roller 31. When the rod 34 is rotated counter-clockwise, the axis of the eccentric 34' moves to the left, with resultant change in position of the rollers 33 toward the rollers 31 and shifting of position of that portion of the gripper bar to the left, or toward the position shown in dotted lines in Figure 8.

By locating the pairs of rollers toward the center of the channel 20 and of the gripper bar 4, the ends of the latter being held in fixed position within the channel by the cam 16 pressing on the carrier member 10, adjustment of the shaft 34 will cause a bowing of the gripper bar 4 toward its center, which rests upon the rollers, and consequent shifting in position of the gripper fingers carried by the gripper bar. This shifting of position of the gripper fingers, which grip the forward or leading edge of the sheet, will warp the sheet for correcting register, as previously described.

The plate 40 is shown as placed against a graduated scale 44 and having a pointer or indicator formed thereon to cooperate with the scale,

and the bolt 42 serves to lock the plate in adjusted position. Thus the operator can adjust the eccentric shaft 34 to provide the desired bowing of the gripper bar, either in the direction of movement of the cylinder or contrary thereto, and in the degree desired to produce the required warping of the sheet gripped by the gripper fingers for correcting register at the trailing end of the sheet, or for avoiding the wrinkling of sheets that may be ruffled. The adjustment for each unit may be different to properly correct the register as to that printing unit. In practical operation it is usually the third or later units of the multiple unit press which require adjustment, to correct faulty register, but correction to prevent wrinkling may require the adjustment on other units.

Bands 50 may be formed upon the periphery of the gripper bar 4 at the point where it rests upon the rollers 31 and 33 to prevent wear.

The present invention may also be adapted for use in continuous operating sheet fed multiple unit presses employing transfer cylinders. Such a press is shown diagrammatically in Figure 9 of the drawings, wherein the sheets are delivered by the feeder cylinder 101 to an impression cylinder 102, thence to transfer cylinders 103 which deliver the sheet to a second impression cylinder 104 and thence to a final delivery cylinder 105. It is to be understood that the impression cylinders 102 and 104 cooperate with blanket or printing cylinders 106, between which respective couples the sheet travels. In its course from cylinder to cylinder of the press, the sheet is gripped by sets of gripper fingers incorporated in each cylinder which hold the leading edge of the sheet, releasing it when it is transferred to the succeeding cylinder, and is received by the sets of gripper fingers incorporated therein. While only two units have been shown, the invention may be applied to a press having any desired number of units.

In Figure 10 is illustrated a top plan view of an impression cylinder 104 incorporating a gripper bar 110 to which is attached a plurality of sheet gripping units 111. The gripper bar 110 together with its associated gripping mechanism is located in a channel 112 formed in the body of the cylinder 104 longitudinally thereof and at its surface. The bar 110 is rigidly anchored in place in any suitable manner, as by means of the bolts 113 which extend through the end plates of the cylinder 104 into the bar.

The sheet gripping units 111 comprise blocks 114 securely attached to the bar 110 at intervals 55 along its length and having gripping elements 115. A shaft 116 extending parallel to the bar 110 is journaled in the blocks 114 of the gripping units 111. To this shaft 116 are rigidly attached gripping fingers 117 for cooperation with the elements 115 of the blocks 114. Rotation of the shaft 116 opens and closes the grippers, by establishing or releasing the contact between the fingers 117 and the block element 115, as desired. The shaft 116 may be journaled at one end in the end plate of the cylinder 104 and its opposite end extends through the end plate at the other end of the cylinder 104. To this end of the shaft 116 is attached a rocker arm 120, one end of which is connected to a spring biased rod 121, while the other end carries a cam roller 122 cooperating with a cam surface 123 attached to the frame of the press. This cam surface is so arranged as to rotate the arm 120 against the bias of the spring 124 at predetermined intervals during rotation of the cylinder 102, thus rotating

the shaft 116 sufficiently to open and close the gripping jaws of the units 111. The mechanism forms no part of the present invention and any satisfactory mechanism for operating the gripper units may be substituted.

On the opposite side of the gripper bar 110 and at its center is attached a block 130 having a bore in which is inserted a crank rod extension 131. The extension 131 is formed at one end of a crank 132 attached to a rod 133 which extends parallel to the bar 110 to one end of the cylinder 102. The rod 133 is journaled in an extension 134 formed in the side wall of the channel 112 and extends through the end plate of the cylinder 104.

On the end of the rod 133 extending beyond the end of the cylinder 104 is attached a rocker arm 135 (Fig. 11) which is keyed to the rod 133 for movement therewith. At the end of the rocker arm 135 is rotatably attached an arm 136 having a bore at its lower end for rotatably receiving a bolt 137 and sleeve 138 (Fig. 13), the arm 136 rotating freely on said sleeve.

A rocker arm 140 is pivotally mounted on the end of the cylinder 104 by means of a pivot 141 which rotates within a corresponding bore 142 formed in the end of the cylinder 104. An arcuate T-slot 143 is formed in the body of the pivotal arm 140 to receive the bolt 137 and the sleeve member 138, which may be adjustably positioned therein and locked in place by tightening the bolt 137, so as to press against the bottom of the slot 143.

One end of the rocker arm 140 is attached to a spring biased rod 145 which slidably fits within a block 146 attached to the end of the cylinder 104. The pressure of the spring 147 exerted against the block 146 and a collar 148 secured to the rod 145 constantly urges the arm 140 to turn counter-clockwise as seen in Fig. 11.

The opposite end of the arm 140 carries a cam roller 150 which cooperates with a cam track or surface 151, the latter being rigidly attached to the frame of the press or otherwise suitably fixed in place. As the roller 150 rides over the cam surface 151, the arm 140 will be rocked when the cam surface rises (as at 152). The configuration of the cam surface may be designed with any number of rises, according to the number of times per rotation of the cylinder 104 it is desired to bend the gripper bar 110. The spring biased rod 145 serves to keep the cam roller in continuous contact with the cam surface.

When the axis of the bolt 137 and sleeve member 138 is in line with the axis of the pivot member 141, the rocking of the arm 140 will have no effect on the associated parts. However, when the bolt 137 is loosened and moved to the right or left of the axis of the pivot 141, movement of the rocker arm 140 will serve to raise or lower the end of the arm 135 and rotate the shaft 133. The arm 136 has an indicator on its lower end which cooperates with a scale placed on the arm 140 to indicate the relative positions of the two axes.

When the arm 136 is pivoted at a point to the right of the pivot center of the arm 140, as seen in Fig. 11, the arm 136 will be pulled downward by the action of the cam, rotating the crank shaft 133 clockwise and bowing the center of the gripper bar forward, or in the direction of rotation of the cylinder 104, warping the sheet held thereby in such a manner as to draw the trailing corners of the sheet inward to correct lack of register due to the trailing edge of the sheet having spread.

When the arm 136 is pivoted on a point to the left of the pivot center of the arm 140, the cam will act to raise the arm 135, rotating the crank shaft 133 counterclockwise, and through its crank member 132 will bend the gripper bar 110 backward at its center. This will cause the paper gripped by the units 111 to be bowed at its center to warp the trailing corners of the sheet outward, thus correcting register where the trailing edge of the sheet has shrunk due to conditions previously pointed out.

The degree of bowing of the bar 110 and the extent that the paper is warped in either direction is controlled by the setting of the pivot point of the arm 136 within the arcuate slot 143. The scale is provided for the operator's use in setting the mechanism to provide the desired extent of bowing.

In Figures 9 and 11 a center line 160 is shown through the axis of the cooperating cylinders 104 and 106, the impression and blanket cylinders respectively, bisecting the point of impression. In operation it is desirable that the sheet be warped into proper aligned shape before its leading edge reaches the point of impression. To accomplish this end, the cam surface is so constructed that its high portion of about 60° of its circumference, is engaged by the roller 150 through an arc before and after the grippers have passed the impression point, or line of centers 160. Thus the gripper bar will be bowed in the desired direction just before the leading edge of the sheet, gripped by the gripper bar mechanism, reaches the point of impression. The cam will act to release the action of the bowing mechanism shortly after the leading edge of the sheet has passed the impression point. Regardless of the cylinder to which the structure is applied, the warping action should begin before the sheet reaches the point of impression.

In the chain conveyor type of press described in connection with Figure 3, the gripper bar is carried through the successive units and holds the sheet throughout its passage through the unit. Accordingly, the flexure of this bar by comparison with its flexure, if any, at the time when it receives the sheet from the sheet registering and feeding unit determines the distortion to which the sheet is subjected at any given unit.

In the transfer cylinder type of press, described in connection with Figure 9, the sheet is passed along from cylinder to cylinder, the grippers of each cylinder surrendering the sheet to the grippers of the succeeding cylinder. In this type of construction, therefore, the leading edge of the sheet may be distorted at any desired point and passed along to succeeding grippers which are thus called upon merely to maintain the distortion. While it is preferred to displace the gripper elements of the impression cylinder after they have received the sheet, it will be clear that this is not necessary. For example, the grippers of a transfer cylinder may be displaced during the time when the sheet is being surrendered to a succeeding cylinder and the sheet will then be carried through to the impression point in its distorted condition. Alternatively, if the grippers are displaced when receiving the sheet, merely permitting them to return to their normal position will impart the desired distortion. While it is preferred to displace the gripping elements of the impression cylinder in the manner shown, similar effects can be obtained by displacing the gripper elements of the transfer or registering cylinder.

If desired, means may be provided for adjusting the bowing of the gripper bar in either form of the invention while the press is running. The modified mechanism of Figures 14 and 15 illustrates one form of device suitable for this purpose, and is shown as applied to the conveyor type of press. The cylinder 12, and the chain conveyor, as well as the gripper bars and the rollers and shafts supporting the same, being the same as in Figures 4 and 7, require no further description. Instead of adjusting the shaft 34 by means of a member fixed to the cylinder and rotatable therewith, an arrangement is provided for adjusting the angle of this shaft as the leading edge of the sheet approaches and until it passes the impression line of the printing cylinder. This adjustment is effected by means of a cam 200 affixed to the frame structure 201 as by means of supports 202 and having an adjustable section 203 pivoted at one of the supports 202, as indicated, and movable through a range of adjustment by means of the rod 204. The rod 204 is pivotally connected to the adjustable cam section 203 at 205 and is adjusted by means of a hand wheel 206 secured to a screw-threaded bushing having a collar 207. A poppet 208 mounted on the frame 201 as by means of a support 209 prevents movement of the rod 204, except by rotating the handwheel. By this means, the rise or fall of the cam 200—203, through the appropriate arc of the cylinder, may be adjusted as desired. A roller 210 is carried by an arm 211 keyed to the shaft 34, and is pressed against the cam by the spring 212. The angular position of shaft 34 and hence the position of the gripper bar supporting rollers is thus determined by the adjustment of the cam. With the cam section 203 adjusted as shown, the gripper bar will be bowed before and for a short time after the leading edge of the sheet reaches the impression point so as to advance the center of the sheet and thus contract the trailing edge as before described.

What I claim is:

1. In multiple unit offset printing, the method of correcting for expansion of the trailing end of a sheet following a first impression, which comprises leading the sheet through a later printing couple with the middle of the leading edge of the sheet advanced with reference to the corners, whereby the trailing end of the sheet is contracted to bring the first impression into register with that of the later printing couple.

2. In multiple unit rotary printing on a machine of the type in which sheets to be printed are carried through the printing couples by gripper bars having gripping elements settable for gripping and holding the leading edge of a sheet at points spaced across its width, the method of adjusting the trailing end of a sheet for register which comprises bowing a gripper bar carrying the sheet, in a direction to curve the leading edge of the sheet in a plane tangent to its path of travel, before it reaches an impression point and during part of the passage of a sheet therethrough, whereby a later impression is brought into register with a previous impression.

3. In multiple unit rotary printing on a machine of the type in which sheets to be printed are carried through the printing couples by gripper bars having gripping elements settable for gripping and holding the leading edge of a sheet at points spaced across its width, the method of adjusting the trailing end of a sheet for register which comprises bowing a gripper bar carry-

ing a sheet, in a direction to curve the leading edge of the sheet in a plane tangent to its path of travel, at the impression point and during part of the passage of a sheet therethrough, whereby a later impression is brought into register with a previous impression.

4. In a sheet-fed rotary printing machine, the method of correcting transverse register which comprises shifting the circumferential position of the middle of the leading edge of a sheet with reference to the unit printing cylinder after it leaves one unit of the press and before it is delivered to the succeeding unit thereof, when the trailing end of said sheet has spread or shrunk laterally following a previous impression.

5. In a sheet fed rotary printing machine including a plurality of printing couples and aligned members gripping the sheets at intervals across their leading edges for holding them against the surface of a cylinder of a printing couple, the combination with said gripping members of adjustable means for displacing certain of said gripping members out of alignment with others of said gripping members, whereby the leading edge of the sheet gripped thereby will be warped during its passage through the said printing couple.

6. In a sheet-fed rotary printing machine including a plurality of printing couples and aligned members gripping the sheets at intervals across their leading edges for holding them against the surface of a cylinder of a printing couple, the combination with said gripping members of adjustable means for displacing said gripping members at the middle of the leading edge of a sheet relative to those adjacent its sides, whereby the leading edge of the sheet gripped thereby will be warped during its passage through the said printing couple.

7. In a sheet-fed rotary printing machine including a plurality of printing couples and aligned members gripping the sheets at intervals across their leading edges for holding them against the surface of a cylinder of a printing couple, the combination with said gripping members of adjustable means for displacing said gripping members at the middle of the leading edge of a sheet relative to those adjacent its sides, to alter the alignment of said gripping members circumferentially of the said cylinder, whereby the leading edge of the sheet gripped thereby will be warped during its passage through the said printing couple.

8. In a sheet-fed rotary printing machine including a plurality of printing couples and aligned members gripping the sheets at intervals across their leading edges for holding them against the surface of a cylinder of a printing couple, the combination with said gripping members of adjustable means for displacing said gripping members at the middle of the leading edge of a sheet relative to those adjacent its sides, and cam means affixed to the machine frame for operating said adjustable means, whereby the leading edge of the sheet gripped thereby will be warped during its passage through the said printing couple.

9. In a sheet-fed rotary printing machine including a plurality of printing couples and aligned members gripping the sheets at intervals across their leading edges for holding them against the surface of a cylinder of a printing couple, the combination with said gripping members of means for displacing said gripping members at the middle of the leading edge of a

11

sheet relative to those adjacent its sides, and adjustable means affixed to the machine frame for operating the last said means, whereby the leading edge of the sheet gripped thereby will be warped during its passage through the said printing couple.

10. In a sheet-fed rotary printing machine including a plurality of printing couples, and in combination, members for gripping the sheets to be printed at intervals across their leading edges for holding them against the surface of a cylinder of a printing couple, a bar carrying said gripping members, the said gripping members being arranged for holding the portions of the sheet gripped thereby at fixed distances from the bar and adjustable means for bowing the said bar.

11. In a sheet-fed rotary printing machine including a plurality of printing couples, and in combination, members for gripping the sheets at intervals across their leading edges for holding them against the surface of a cylinder of a printing couple, a bar carrying said gripping members, means embodied in the printing couple for supporting said bar, and adjustable means carried by said supporting means at the end of the cylinder for bowing said bar whereby the alignment of the gripping members attached thereto may be altered for warping the sheet gripped thereby during its passage through said couple.

12. In a sheet-fed rotary printing machine including a plurality of printing couples, and in combination, members for gripping the sheets at intervals across their leading edges for holding them against the surface of a cylinder of a printing couple, a bar carrying said gripping members, means embodied in the printing couple for supporting said bar, adjustable means carried by said supporting means for bowing said bar, and cam means affixed to the machine frame for operating said adjustable means, whereby the alignment of the gripping members attached thereto will be altered for warping the sheet gripped thereby during its passage through said couple.

13. In a sheet-fed rotary printing machine including a plurality of printing couples, and in combination, members for gripping the sheets at intervals across their leading edges for holding them against the surface of a cylinder of a printing couple, a bar carrying said gripping members, means embodied in the printing couple for supporting said bar, means carried by said supporting means for bowing said bar, and adjustable means affixed to the machine frame for operating the last said means, whereby the alignment of the gripping members attached thereto will be altered for warping the sheet gripped thereby during its passage through said couple.

14. In a sheet-fed printing machine including a plurality of printing couples, and in combination, conveyor means for feeding the sheets through the printing couples, a gripper bar carried by said conveyor means, gripping members carried by said bar for gripping the sheets across their leading edges, and adjustable means for bowing said bar, whereby the alignment of the said gripping members will be altered to warp the leading edge of a sheet during its passage through a printing couple.

15. In a sheet-fed printing machine including a plurality of printing couples, and in combination, conveyor means for feeding the sheets through the printing couples, a gripper bar carried by said conveyor means, gripping members carried by said bar for gripping the sheets across

12

their leading edges, adjustable means for bowing said bar, and cam means affixed to the machine frame for operating said adjustable means, whereby the alignment of the said gripping members will be altered to warp the leading edge of a sheet during its passage through a printing couple.

16. In a sheet-fed printing machine including a plurality of printing couples, and in combination, conveyor means for feeding the sheets through the printing couples, a gripper bar carried by said conveyor means, gripping members carried by said bar for gripping the sheets across their leading edges, means for bowing said bar, and adjustable means affixed to the machine frame for operating the last said means, whereby the alignment of the said gripping members will be altered to warp the leading edge of a sheet during its passage through a printing couple.

17. In a sheet-fed printing machine, and in combination, a cylinder, gripping members carried thereby for gripping sheets across their leading edges, and a plurality of relatively adjustable means spaced across the cylinder for displacing said gripping elements at the middle of the leading edge of a sheet relative to those adjacent its sides, whereby the center portion of the leading edge of the sheet may be advanced or retarded.

18. In a sheet-fed printing machine, and in combination, an impression cylinder, gripping members carried thereby for gripping sheets across their leading edges, and a plurality of relatively adjustable means spaced across the cylinder for displacing said gripping elements at the middle of the leading edge of a sheet relative to those adjacent its sides, whereby the center portion of the leading edge of the sheet may be advanced or retarded.

19. In a sheet-fed printing machine, and in combination, an impression cylinder, gripping members carried thereby for gripping sheets across their leading edges, adjustable means for displacing said gripping elements at the middle of the leading edge of a sheet relative to those adjacent its sides, and comprising co-operating members upon said cylinder and upon the machine frame, whereby the center portion of the leading edge of the sheet may be advanced or retarded while the said gripping elements are passing through a predetermined arc of movement including the impression point.

20. In a sheet-fed printing machine, and in combination, a cylinder having a channel for a gripper bar, means within said channel for bowing said bar, the said means comprising a plurality of relatively adjustable elements for engaging the bar toward its ends and toward its middle, and means at the end of said cylinder for adjustably positioning the said adjustable elements.

21. In a sheet-fed printing machine, and in combination, a cylinder having a channel for a gripper bar, means within said channel for bowing said bar, means associated with said cylinder for operating said bar to grip and release sheets, and means at the end of said cylinder and operating in timed relation to the last said means for adjustably operating the said bowing means.

22. In a sheet-fed printing machine, and in combination, a printing cylinder, a cooperating impression cylinder having a channel for a gripper bar, means within said channel for bowing said bar, the said means comprising a plurality of relatively adjustable elements for en-

13

gaging the bar toward its ends and toward its middle, and means at the end of said cylinder and operating through a predetermined arc before and after the impression point for adjustably positioning the said adjustable elements.

23. In a sheet-fed printing machine, and in combination, a cylinder having a channel for a gripper bar, means within said channel for bowing said bar and comprising a shaft carrying a plurality of eccentric bowing elements and arranged relative to said bar for deflecting the middle thereof in the same direction relative to both of its ends upon angular movement of the shaft, and means at the end of said cylinder for adjusting the angular position of the said shaft to operate the said bowing means.

24. In a sheet-fed printing machine, and in combination, cooperating cylinders, a set of gripping members carried on one of said cylinders, a set of gripping members carried on the other of said cylinders, means for driving said cylinders in timed relation, means for transferring sheets from the gripping members of one of said cylinders to those of the other said cylinder, and means for altering the alignment of one of said sets of gripping members, relative to the alignment thereof at the time of the said transfer, for warping the leading edge of a sheet, the last said means comprising a plurality of adjustable means spaced across one of the said cylinders and operable to position the gripping members of one of said sets so as to deflect the middle members thereof relative to both end members.

25. In a sheet-fed printing machine, and in combination, a cylinder, a gripper bar carried thereby, gripping members attached to said bar and spaced therealong for gripping a sheet across its leading edge, and means for bowing said bar during its passage through a predetermined arc of movement of said cylinder, the last said means comprising means for engaging the middle of the bar and deflecting the same in the same direction relative to both of its ends.

26. In a sheet-fed printing machine, and in combination, a cylinder, a gripper bar carried thereby, gripping members attached to said bar and spaced therealong for gripping a sheet across its leading edge, means for bowing said bar during its passage through a predetermined arc of movement of said cylinder, the last said means comprising means for engaging the middle of the bar and deflecting the same in the same direction relative to both of its ends, and adjustable means at the end of the said cylinder for operating the said bowing means.

14

27. In a sheet-fed printing machine, and in combination, a cylinder, a gripper bar carried thereby, gripping members attached to said bar and spaced therealong for gripping a sheet across its leading edge, means for bowing said bar during its passage through a predetermined arc of movement of said cylinder, the last said means comprising means for engaging the middle of the bar and deflecting the same in the same direction relative to both of its ends, and cooperating adjustable means at the end of said cylinder and upon the machine frame for operating the said bowing means.

28. In a sheet-fed rotary printing machine including impression and printing cylinders, members gripping the sheets at intervals across their leading edges, a gripper bar carrying and actuating said gripping members, and a conveyor mechanism for said gripper bar, the said impression cylinders having channels for receiving said gripper bar, the combination with an impression cylinder of means located in a said channel for supporting and bowing said gripper bar, and adjustable means at the end of the impression cylinder for operating the last said means.

29. In a sheet-fed rotary printing machine including impression and printing cylinders, members gripping the sheets at intervals across their leading edges, a gripper bar carrying and actuating said gripping members, and a conveyor mechanism for said gripper bar, the said impression cylinders having channels for receiving said gripper bar, the combination with an impression cylinder of means located in a said channel for supporting and bowing said gripper bar, the said means including rollers within said channel for supporting the said gripper bar, an eccentric shaft carrying said rollers, and adjustable means at the end of the impression cylinder for varying the angular position of said shaft.

ALEXANDER J. ALBRECHT.
